NOZZLE FOR OIL OR OTHER LIQUID

William A. Hubbard, Minneapolis, Minn.

Application April 21, 1934, Serial No. 721,749

15 Claims. (Cl. 299—120)

This invention relates to a nozzle and while the nozzle may have various applications and be used for various liquids, it particularly is designed for use with an oil burner. Such nozzles are now used in large numbers and have the oil forced therethrough under pressure. It is desirable in such a nozzle to have one which can be easily and quickly removed for cleaning or replacement. It is also desirable to have a nozzle containing a screen for straining the oil, which screen should be firmly mounted by a simple structure and be also easily and quickly removable. It is also quite desirable to have parts of the nozzle easily removable from the outer end of the nozzle.

It is an object of this invention to provide a nozzle structure having a member forming the head or outer end of the nozzle adapted to be secured in or threaded into a nozzle shell, which member carries all of the nozzle parts including a screen whereby the same can be easily and quickly removed.

It is a further object of the invention to provide a nozzle comprising an outer member adapted to be threaded into a shell at one end, having its other end forming the outer end of the nozzle and preferably tapering to its outer end, said member having a discharge disk seated therein, a second member threaded into the inner end of said member holding said disk in place and having a bore therein in which a screen is disposed, a headed member being provided to extend through and engage said screen and hold it in place in said second member.

It is still another object of the invention to provide a novel mounting for a nozzle screen comprising a member having a bore therein with a shoulder at one end against which one end of the screen seats and a headed member extending through said screen threaded into said first mentioned member at one end and engaging said screen with its headed portion to hold the same against said first mentioned member.

It is a further object of the invention to provide a structure as set forth in the preceding paragraph in which said headed member has an annular groove in its head in which one end of said screen is received, said first mentioned member preferably having its bore tapering at one end to center the other end of said screen.

These and other objects and advantages of the invention will be fully set forth in the following description made in connection with the accompanying drawing, in which like reference characters refer to similar parts throughout the several views and in which:—

Fig. 1 is a central longitudinal section through the nozzle;

Fig. 2 is a transverse section on line 2—2 of Fig. 1 as indicated by the arrows;

Fig. 3 is a face view of a discharge disk used; 5

Fig. 4 is a transverse section of said disk taken on line 4—4 of Fig. 3 as indicated by the arrows. Referring to the drawing, a nozzle is shown comprising a shell 10. While said shell may take various shapes, in the embodiment of the invention illustrated, it is shown as having a cylindrical outer portion 10a interiorly threaded as shown at 10b. Said nozzle has an outer portion 10c preferably of hexagonal or other angular shape and also bored and internally threaded as shown at 10d. The shell 10 is adapted to be screwed onto a liquid supplying or oil supplying pipe. The nozzle also comprises a member 11 having a reduced and externally threaded inner portion 11a adapted to be threaded into the outer end of shell 10. Said member 11 has a shoulder portion 11b engaging the end of shell 10. Member 11 has the portion adjacent the end of the shell 10 preferably made of hexagonal or other shape and the same has an end portion 11c of substantially cylindrical shape, the same converging toward the outer end of the nozzle. Said latter portion has an opening 11d extending axially therethrough, the walls of said opening being formed on a reentrant curved surface 11e continuous with the outer surface of portion 11c. Member 11 is provided with a longitudinal central bore and is formed adjacent the opening 11d with an angular shoulder 11f. A discharge disk 35

12 of flat cylindrical form has one corner beveled so that said disk fits against shoulder 11f and in the bore of member 11, said disk thus extending across opening 11d. Said disk is provided with a quite small central discharge aperture 12a of cylindrical form and also has a frusto-conical portion 12b extending from the inner end of the cylindrical passage 12a to the inner side of the disk, passage 12b flaring inwardly. Said disk has an annular groove 12c at its inner side of semi-circular form in radial cross section and a pair of small grooves 12d lead from the groove 12c inwardly to passage 12b and are disposed tangentially to said passage at opposite sides thereof. Member 11 is interiorly threaded at 11g and a member 13 is exteriorly threaded and screwed into member 11. Member 13 has a flat surface at its inner end which engages the inner side of disk 12 and holds the same against shoulder 11f, member 13 being screwed tight against said 55

disk. Member 13 has a portion 13a of its periphery at its inner end formed of hexagonal or other angular shape so that it can be readily turned. The portion 13b between portion 13a and the exteriorly threaded portion is preferably cylindrical. Member 13a is provided with a central bore 13c which has a reduced interiorly threaded portion 13d, said bore being somewhat enlarged at the outer side of the portion 13d to form the chamber 13e. A shoulder 13f is formed adjacent the reduced threaded portion 13d and the wall of bore 13c converges toward this shoulder at the inner end of said bore as shown at 13g. A plurality of holes 13h are formed in the outer end 15 of member 13, the same being shown as two in number, said holes alining at their outer end with the groove 12c. A screen 14 is provided and while the screen might have various shapes, in the embodiment of the invention illustrated, it is shown 20 as cylindrical in form. The outer end of screen 14 seats against shoulder 13f, the exterior diameter of said screen being substantially the same as the reduced portion of the inner end of bore 13c. A member 15 is provided having an enlarged portion or head 15a provided at its outer side with an annular groove 15b in which the inner end of screen 14 is disposed. Member 15 has a threaded shank portion 15c extending through the screen 14 and threaded into portion 30 13d. Member 15 thus holds the screen 14 firmly against the shoulder 13f and said screen is thus positioned axially of members 11 and 13. Member 15 is screwed into member 13 until screen 14 is firmly engaged. Member 15 has a pair of 35 grooves 15d extending longitudinally thereof at opposite sides substantially throughout the length of its threaded shank portion 15c. Member 15 has a tapered frusto-conical portion at its end in the surface of which grooves 15d terminate.

In operation, as stated, the member 10 will be secured to an oil supplying pipe or conduit and connected thereto by the threads 10d. The oil or other liquid passes into the shell 10, then passes 45 through screen 14 from the outer side to the interior thereof and enters the grooves 15d. The oil or other liquid then flows into chamber 13e, through holes 13h to the groove 12c, through grooves 12d to the discharge passages 12b and 50 12a and is discharged in the form of an outwardly diverging cone from passage 12a. It will be seen that if it is desired to dismantle the nozzle for any purpose the member 11 can be unscrewed from the shell 10. This can readily be done with- 55 out disconnecting the shell 10 from its supply pipe. When member 11 is thus removed it carries with it the parts 12, 13, 14 and 15. If the screen is to be removed this can be easily done by removing member 15. The screen can thus be re- 60 moved for cleaning or replacement very easily and quickly. If it is necessary to remove the disk 12 this can readily be done by unscrewing and removing member 13. It will also be apparent that the whole nozzle assembly including parts 11 to 65 15 can be assembled and in operative condition before the same are placed in the shell 10. Said parts thus constitute a unitary structure. In practice these parts, which, as stated, are carried by the member 11, are made as a separate 70 unit or article of manufacture and are sold in this form to be connected to various shells 10.

From the above description it is seen that applicant has provided a very simple and efficient form of nozzle and one that can be very readily assembled and dismantled. The parts are all 75

accessible when the member 11 is removed from the outer end of the nozzle. The parts are all simple and of rugged construction and comparatively few in number. The nozzle has been amply demonstrated in actual practice, has been found to be very successful and efficient and is being commercially made.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims. 15

What is claimed is:—

1. An oil burner construction comprising a plug adapted to be threaded into a nozzle head and having a central bore extending from one end thereinto and having a reduced threaded 20 portion at the inner end of said bore, a cylindrical screen disposed in said bore and spaced from the wall thereof having one end seated in said plug and a member extending through said screen having one end threaded into said last 25 mentioned portion and having an enlarged portion engaging the other end of said screen for holding said screen in place.

2. The structure set forth in claim 1, said member having an annular groove in said enlarged portion into which the end of said screen projects.

3. The structure set forth in claim 1, said bore having a shoulder at one end and said bore tapering toward said shoulder whereby the end of said screen is guided to a substantially central position and held in said bore against said shoulder.

4. A nozzle construction comprising a member having a central longitudinal bore extending therethrough and having an externally threaded 40 portion at one end adapted to be screwed into a nozzle shell, the other end of said member forming the outer end of said nozzle, said member having a shoulder therein a short distance from its other end, a discharge disk fitting against 45 said shoulder and having a small central discharge aperture therethrough, a second member threaded into said bore having its end engaging said disk to hold the same against said shoulder, said second member having a bore there- 50 through, a cylindrical screen disposed in said bore and spaced from the walls thereof, a member engaging one end of said screen and threaded into said second member to hold said screen in place, said latter member having passages ther- 55 through through which liquid passing through said screen may pass to one end of said first mentioned bore and said first mentioned member having means for the passage of liquid to said discharge disk. 60

5. A nozzle construction comprising a member externally threaded at one end so as to be screwed into one end of a nozzle shell and having its other end forming the outer end of said nozzle, a second member extending into said first mentioned end of said first mentioned member threaded thereto and having a central longitudinal bore, a cylindrical screen, and means extending longitudinally within said screen and having a threaded portion secured to said sec- 65 ond mentioned member for holding said screen in place, whereby all of said parts are carried by said first mentioned member.

6. A nozzle construction comprising a member arranged to have one end screwed into a nozzle 70

- shell and having its other end forming the outer end of said nozzle, said member having a bore extending therethrough, an apertured discharge means in said member adjacent its outer end, 5 a second member threaded into said first mentioned member from said first mentioned end, a screen engaging said second member, and means secured to said second member and threaded thereto from its inner end engaging said screen 10 for holding said screen in place against said second member whereby said first mentioned member may be screwed out of said shell and carry therewith said second member, screen and means.
7. A nozzle structure comprising a hollow open-ended member adapted to be secured in a nozzle shell at one end and having its other end forming the discharge end of said nozzle, a discharge disk extending across the opening at said discharge end, a second member threaded into said 15 member from said first mentioned end holding said disk in place, said second member having a longitudinal bore, a screen and a third member threaded to be secured to said second member and holding said screen in place with one end abutting said second member whereby said first mentioned member carries all of said parts and may be screwed into and out of said nozzle shell to give access to said parts.
8. A nozzle structure comprising a hollow open-ended member adapted to be screwed into a nozzle shell at one end and having its other end forming the discharge end of said nozzle, a discharge disk extending across the opening at said discharge end, a second member threaded 20 into said member from said first mentioned end, said second member having a longitudinal bore, a screen through which oil passes to said bore and a third member threadedly connected to said second member and engaging the inner end of 25 said screen for holding said screen in place whereby all of said parts are carried by said first mentioned member.
9. A nozzle structure comprising a hollow open-ended member adapted to be screwed into a nozzle shell at one end and having its other end forming the discharge end of said nozzle, a discharge means extending across the opening at said discharge end, a second member threaded into said member from said first mentioned end, 30 said second member having a longitudinal bore, a screen through which oil passes to said bore and a member secured to said second member and engaging the end of said screen remote from said discharge end for holding the same in place.
10. An oil burner structure comprising a hollow open-ended member adapted to be secured in a nozzle shell at one end, having its other end forming the discharge end of the nozzle, a discharge disk extending across the opening at said discharge end, a second member threaded into said member from said first mentioned end holding said disk in place, a cylindrical screen, and means secured to said second member for hold-

ing said screen in place including a member extending lengthwise of said screen within the same and engaging one end of said screen.

11. A nozzle construction having in combination, a nozzle shell having a bore extending therethrough and internally threaded at one end, a member externally threaded so as to be screwed into said end of said shell and having its other end forming the outer end of said nozzle, said member having a bore therein, a cylindrical 10 screen disposed in said latter bore and spaced from the walls thereof having one end seated in said member and a second member extending through said screen having one end threaded into said first mentioned member and having an 15 enlarged portion engaging the other end of said screen for holding said screen in place.

12. A nozzle structure comprising a hollow open-ended member adapted to be screwed into a nozzle shell at one end and having its other end 20 forming the discharge end of said nozzle, a second member threaded into said member from said first mentioned end, said second member having a longitudinal bore, a screen through which oil passes to said bore and means extending through said screen and threaded to said second member and engaging the end of said 25 screen remote from said discharge end to hold the same in place so that said screen may be released and removed upon removal of said last 30 mentioned means.

13. A nozzle structure comprising a hollow open-ended member adapted to be screwed into a nozzle shell at one end and having its other end forming the discharge end of said nozzle, a 35 second member threaded into said member from said first mentioned end, said second member having a longitudinal bore, a screen engaging said second member and through which oil passes to said bore and means secured to said second member and loosely engaging said screen to clamp the same in place against said second member whereby said screen will be loose and separate when said last mentioned means is detached from said second member.

14. A nozzle having a shell and comprising a member disposed in said shell, said member having an opening extending longitudinally thereof, a cylindrical screen having one end engaging said member, a second member secured in said first 50 mentioned member extending through said screen and having means engaging the other end thereof to hold said screen in place.

15. A nozzle having a shell and comprising a member carried concentrically thereon, said 55 member having an opening extending longitudinally thereof for the passage of liquid, a cylindrical screen having one end abutting said member and a second member extending longitudinally through said screen engaging one end thereof to hold the same in place and centrally threaded into said first mentioned member.

WILLIAM A. HUBBARD.
